UNITED STATES PATENT OFFICE.

ROBERT STUART OWENS, OF BROOKLYN, NEW YORK.

DESIGN FOR AN INDIVIDUAL FLOWER-HOLDER.

50,112.

Specification for Design.

Patented Dec. 26, 1916.

Application filed March 24, 1916. Serial No. 86,515. Term of patent 3½ years.

To all whom it may concern:

Be it known that I, ROBERT STUART OWENS, a citizen of the United States, residing at Brooklyn, in the county of Kings and State of New York, have invented a new, original, and ornamental Design for Individual Flower-Holders, of which the following is a specification, reference being had to the accompanying drawing, forming a part hereof.

The figure is a front elevation of an individual flower holder showing my new design.

The lower end of the holder illustrated is

in the form of a partially flattened bulb constituting a base. The neck of the holder decreases in diameter from the base to a point intermediate its length, from which point it gradually increases in diameter to the top where it opens out into the simulation of a flower.

I claim:

The ornamental design for an individual flower holder, as shown and described.

ROBERT STUART OWENS.
